2 Claims. (Cl. 103—128)

This invention relates to screw pumps or other pumping machinery, especially of the sort in which the normally incoming flow has to be split into two streams which normally enter into and flow through the pumping element, e.g., rotating screws in opposite directions to each other. It is an object of the invention to provide a pump of increased life and easier maintenance than known pumps.

It is desirable to have the portion of the walls of the pump casing which is in contact with or in close proximity to the screws or other pumping element replaceable since this forms the wearing area of the pumping chamber. The present invention achieves the foregoing by providing a casing having an open end, removable means for closing the open end, a hollow open ended tubular insert constituting a pumping chamber within the casing spaced at both ends thereof from the ends of the casing, intermeshing symmetrical double-ended counter-rotating screw-threaded rotors closely fitting in the chamber for pumping a fluid through the chamber, first and second opposed lateral extensions integral with the tubular insert bearing against internal surfaces of the casing for spacing the pumping chamber laterally from the casing, said casing having a first port at one end communicating directly with the respective end of the pumping chamber and a second port laterally disposed and aligned with said first extension, said first extension being provided with a laterally extending port interconnecting said pumping chamber and second port, said second extension being provided with a longitudinally extending passage interconnecting the ends of the casing so that said first port communicates with both ends of the pumping chamber, said first extension sealing the laterally extending port from the interior of the casing, and said insert and first and second lateral extensions being slidable within the casing whereby the insert and extensions can be removed bodily from the casing through the open end thereof upon removal of the removable means.

A counterflow screw pump embodying the invention will now be described with reference to the accompanying drawing, in which:

FIGURE 1 is an axial cross section of a screw pump;
FIGURE 2 is a cross section on line II—II of FIGURE 1, the pump rotors being omitted.

The pump, as is usual, includes two or more parallel double-ended meshing screw threaded rotors 1 on shafts 19 rotating in opposite directions inside a pumping chamber 2 of figure-8 cross-section as shown in FIGURE 2. The chamber is formed in an insert 3 which has a tubular body 6 open at each end to form inlet ports 4 and has a single lateral extension constituting an outlet port 5 at its mid point. Integral with the tubular body 6 on the side opposite the outlet port is an arcuate lateral extension 7 defining a passage 9 parallel to the rotors 1.

The pumping chamber insert 3 is disposed inside a main pump casing 10 having a generally cylindrical tubular form. The casing is spaced from the insert at each end so as to define suction bays 11 communicating with the inlet ports 4, and the outlet port 5 of the chamber communicates with an outlet branch 12 of the casing.

2

The outlet port 5 and the extension 7 on the opposite side of the insert fit closely in the casing 10 to provide a seal between the high and low pressure areas of the main casing, i.e., the suction bays and outlet branch.

A single inlet branch 13 is provided at one end of the casing and communicates directly with the suction bay 11 at that end of the casing. Fluid can flow from the inlet branch to the other suction bay through the passage 9 defined by the extension 7 as shown by the arrows 14 in FIGURE 1. An end of the casing is detachable, so that the pumping chamber can be removed bodily from the casing.

In the drawing this is shown at the end remote from the inlet branch, the main body of the casing 10 ending in flanges 15 to which flanges 16 of an end piece 17 are attached, for example by bolts 18.

It will be understood that the pump shown is merely exemplary and that other arrangements are possible. For example the passage 9 could be defined partly by the wall of the casing instead of being wholly within the insert, with the arcuate projection 7 being replaced by one or more solid projections serving the same function of spacing the body 6 from the casing 10. In such a case the inlet branch 13 could be arranged centrally.

25 I claim:

1. A counterflow screw pump including a casing having an open end, removable means for closing the open end, a hollow open ended tubular insert constituting a pumping chamber within the casing spaced at both ends thereof from the ends of the casing, intermeshing symmetrical double-ended counter-rotating screw-threaded rotors closely fitting in the chamber for pumping a fluid through the chamber, first and second opposed lateral extensions integral with the tubular insert bearing against internal surfaces of the casing for spacing the pumping chamber laterally from the casing, said casing having a first port at one end communicating directly with the respective end of the pumping chamber and a second port laterally disposed and aligned with said first extension, said first extension being provided with a laterally extending port interconnecting said pumping chamber and second port, said second extension being provided with a longitudinally extending passage interconnecting the ends of the casing so that said first port communicates with both ends of the pumping chamber, said first extension sealing the laterally extending port from the interior of the casing, and said insert and first and second lateral extensions being slidable within the casing whereby the insert and extensions can be removed bodily from the casing through the open end thereof upon removal of the removable means.

2. The counterflow screw pump as claimed in claim 1 in which said first port is at that end of the casing remote from the open end thereof and said second part and laterally extending port are located at the midpoint of the casing and pumping chamber, respectively.
